UNITED STATES PATENT OFFICE.

JOSEPH G. SUTTON, OF SENECA, MISSOURI, ASSIGNOR TO AMERICAN TRIPOLI COMPANY, OF SENECA, MISSOURI, A CORPORATION.

WATER-FILTER.

No. 796,266.

Specification of Letters Patent.

Patented Aug. 1, 1905.

Application filed December 2, 1904. Serial No. 235,136.

To all whom it may concern:

Be it known that I, JOSEPH G. SUTTON, a citizen of the United States, residing in Seneca, in the county of Newton and State of Missouri, have invented certain new and useful Improvements in Water-Filters, of which the following is a full, clear, and exact description, reference being had to the accompanying drawings, forming part of this specification.

My invention relates to that character of water-filters adapted to be connected to house water-service pipes for the purpose of supplying household needs for filtered water, the object of the invention being to make a filter of simple construction and one in which the filter-cylinder may be readily withdrawn from the case in which it seats without the water present in the filter-case being withdrawn with the filter-cylinder, but instead being allowed to discharge from the lower end of the case.

Figure I is a vertical section taken through my filter. Fig. II is a cross-section taken on line II II, Fig. I. Fig. III is a vertical section of a modified form of my filter.

1 designates the case of the filter, which is preferably of cylindrical shape. The upper mouth end of the cylinder is open and the lower or outlet end of the cylinder is contracted to furnish a funnel-shaped discharge-neck 2. The contracted neck is preferably soldered to the filter-case, and it serves to prevent splashing of water when the filter-cylinder is removed from the case. At the upper and lower ends of the case are annular outwardly-presented beads 3, that serve to provide annular pockets 4 at the interior of the case. These pockets receive packing-rings 5, preferably of rubber, and the interior diameter of which is less than the interior diameter of the filter-case, as seen in Fig. I.

6 designates a filter-cylinder, preferably of tripoli stone, and 7 is a perforated tube extending longitudinally through the said filter-cylinder.

8 is an end cap, that is fitted to the lower end of the filter-cylinder and secured to the lower end of the perforated tube 7, the said end cap having a flange that encircles the stone, as seen in Fig. I. A gasket 9 is preferably introduced between the end cap and the end of the filter-cylinder.

10 is an upper end cap, that is provided with a flange that encircles the upper end of the fil-

ter-cylinder and is connected to the perforated tube, a gasket 11 being preferably introduced between said end cap and cylinder. The upper end cap is also provided with a horizontally-extending annular flange 12, which is adapted to rest upon the upper edge of the filter-case 1.

13 is a discharge-tube, centrally fitted in the upper end cap and having communication with the interior of the perforated tube 7, this discharge-tube serving as an outlet through which the filtered water that percolates through the filter-cylinder into the perforated tube 7 finds escape. The filter may be united to a water-service pipe through any suitable connection attached to a nipple 1^a, projecting from the filter-case.

By constructing the filter as described and placing the packing-rings 4 in pockets in the filter-case, the interior diameter of which is less than the interior diameter of the case, I provide for an annular space between the case and the filter-cylinder therein, from which there is free outlet to the lower discharge end of the case when the filter-cylinder is lifted to remove it from the case, thereby avoiding the possibility of the water in the case being lifted with the cylinder when said cylinder is extracted and overflows the top of the filter-case.

I am aware that filters of the same character as the one herein described have heretofore been made, but in which the packing members are carried by the filter-cylinder. In these constructions the lower packing member rides against the interior of the case when the filter-cylinder is extracted, and therefore the water in the space between the filter-case and filter-cylinder is lifted in a column and discharged over the top of the filter-case, which is an objectionable occurrence I completely overcome in my filter.

In Fig. III, I have illustrated a modification of my filter in which the essential features of my improvement are present, though the filter-cylinder parts are of different construction. In this modification, 1' designates the filter-case, having the contracted neck 2' at its lower end and provided with the beads 3', containing pockets 4', in which the packing-rings 5' are seated. 6' is the filter-cylinder, in which is the perforated tube 7'. 8' is a cement cap that is applied to the lower end of the filter-cylinder, which is cut out to per-

mit of the cap fitting thereinto in order that the cement may secure a firm hold upon the threaded end of the perforated tube 7'. The pores of the cap are suitably closed to prevent seepage of water therethrough. In the center of this cap is a bushing 8^a, that receives a nipple 8^b, through which the filtered water finds escape. 10' is an upper pore-sealed cement cap that is applied to the upper end of the filter-cylinder, which is also cut out to permit of the cap seating therein. The cap 10' contains a bushing 10^a, into which is introduced the shank of a handle 10^b, by which the filter-cylinder may be lifted from its case. This construction is such that, if desired, the filtered water may be discharged from the upper end of the cylinder, the only change necessary being the removal of the handle 10^b in the introduction of a discharge-pipe similar to that 13 and the removal of the nipple 8^b and the substitution of a plug to close the bushing 8^a.

The packing-rings 5, placed in the filter-case as described, are so located that they are not susceptible to injury when the filter-cylinder is introduced into its case or removed therefrom and being loosely fitted in the beads of the filter-case may be readily removed without the employment of any tool and replaced by new ones when they become unfit for further use. The rings fit firmly in the beads, and there is no liability of their becoming displaced when the filter-cylinder is

removed to be cleansed. An additional advantage in placing the packing-rings in the filter-case instead of applying them to the filter-cylinder lies in the fact that when the filter-cylinder is cleansed, usually by the process of brushing it, the packing-rings being entirely absent therefrom are not subjected to the wear that occurs in cleansing the cylinder in constructions wherein the packing-rings are applied to the filter-cylinder. A still further feature of advantage lies in the fact that a more perfect fit of the packing-rings is secured due to the water entering the filter-case acting to seat the packing-rings with greater force into the space between the filter-cylinder and its case, thereby making a more perfect joint that will not permit of the water dripping from the filter.

I claim as my invention—

In a water-filter, the combination of a cylindrical case open at both of its ends and provided at each end with an outwardly-presented bead forming an annular pocket, a filter-cylinder within said cylinder and spaced from the inner wall of the case throughout its entire height, and a packing-ring in each of said pockets and engaging said filter-cylinder at points inwardly from the ends thereof.

JOSEPH G. SUTTON.
